UNITED STATES PATENT OFFICE.

GEORGE W. DOVER, OF LONGMEADOW, RHODE ISLAND, ASSIGNOR TO THE MONTGOMERY TOOL AND MACHINERY COMPANY, A CORPORATION OF RHODE ISLAND.

KNURLING TOOL.

Application filed December 24, 1924. Serial No. 757,915.

This invention relates to an improved knurling tool for use in connection with lathes and the like to knurl material in a novel manner and at a single operation.

5 Tools of this character as heretofore made and used require an initial and repeated thrust or jam against and into the work, which involves increased expense in operation as well as excessive pressure upon the

10 work.

One object of the present invention is the provision of rollers having beveled edges, the edge portions of which are provided with knurling teeth as well as the central 15 portions of the peripheries, whereby the knurling rollers may be set initially to cut knurls of the desired depth and the work may then be fed in front of the rollers to cut the knurls of the desired depth at a 20 single operation.

A further object of the invention is to provide a tool of this character wherein the shank portion is provided with a shoulder adapted to support the roller carrier cage 25 whereby the parts are firmly held against movement of the carrier cage relative to the tool shank during use.

Other objects and advantages of the invention relate to various details of construction and modes of operation as will be more 30 fully set forth in the detailed description to follow.

In the accompanying drawings which form a part of this application:—

35 Fig. 1 is a side elevation of a knurling tool embodying my invention,

Fig. 2, a plan view of the same,

Fig. 3, a section on line 3—3 of Fig. 2,

40 Figs. 4 and 5, a side and an edge elevation respectively of one of the knurling rolls, and,

Fig. 6, a fragmentary section of the same on line 6—6 of Fig. 5.

45 Like reference characters indicate like parts throughout the views.

In the drawings 7 is a tool shank provided at one end with an enlarged rounded portion 9 of reduced thickness as at 10 forming a recess and a resultant curved 50 shoulder 11. The portion 9 has a central opening 13. The cage or carrier-head 15 comprises a hub 16 having spaced webs or flanges 17 provided with peripheral shoulders or arms 18 spaced from each other and 55 having curved outer edges. Fast in each

arm, side by side, are pins 20 which pass loosely through central holes 21 in knurling rollers 22. The hub 16 has a sliding fit in the opening 13 and terminates in a stem 24 provided with a thread 25 engaging the 60 thread 26 of a binding nut 27 whose washer 28 abuts against the face of the enlargement 9. The carrier head 15 fits within the recess 10 so that the shoulder 11 forms an abutment for this member during operation. 65 The countersunk position of this member allows a closer approach to the work, while its ample face bearing prevents excessive strain.

Each knurling roller 22 has an elevated 70 central peripheral portion 30 and inclined peripheral edge portions 31; and transversely disposed upon the peripheral portions, preferably diagonally, are a series of piercing teeth 33, V shaped in cross section 75 which extend across the central peripheral portion and the inclined lateral edges of each roller. The central portion 34 of each tooth is, therefore, elevated and parallel with the axial line of the roll, while both 80 end portions 35 of the teeth are inclined towards the faces of the roll.

In the operation of the tool in knurling, the work to be knurled, which is indicated by the numeral 37 and which is supported 85 along the center line of the lathe, is advanced to a position opposite the knurling tool. Thereupon the locking nut 27 is loosened and the tool advanced until two of the knurling rollers 22 contact with the 90 work as shown in Fig. 1 thus properly positioning the carrier head relative to the tool shank 7. The nut 27 is then tightened to firmly lock the carrier head 15 to the shank 7. 95

The work 37 is then withdrawn from in front of the knurling rollers 22 and the tool post holding the shank 7 advanced by moving the cross-slide an amount depending upon the depth of cut required. The cross 100 slide is then secured in its advanced position. The lathe is now started and the work 37 rotated forwardly against the knurling rollers 22. The provision of knurling rollers having inclined toothed edges 31 enables 105 the work to advance across the faces of the knurling rollers thereby knurling the surface of the work to the desired extent, and also forming a knurl of the desired depth at one operation. 110

Knurling rollers have always been made heretofore with square shoulders which necessitated the positioning of the work in front of the rollers and then jamming the rollers into the work before commencing the knurling operation.

By means of my improved construction the operation is completed by a single traverse of the work and less pressure is required upon the tool.

The construction of the shank 7 provided with a recess 10 and shoulder 11 against which the carrier-head bears transfers the strain upon the knurling rollers directly to the shank 7, and the manner of securing the carrier-head to the tool shank 7 is such as to securely hold the carrier-head against movement.

What I claim is:—

1. A knurling tool provided with cooperating rollers having inclined edges, said rollers being provided with teeth extending across said inclined edges and the central portions of the peripheries thereof, whereby the knurling rollers may be set to cut knurls of the desired depth at a single operation.

2. A knurling tool comprising a shank portion provided with a lateral recess, a shoulder on said shank adjacent to said recess, a carrier-head fixedly secured to said shank and having a portion thereof extending within said recess and bearing against said shoulder, and knurling rollers supported by said carrier-head said rollers being provided with teeth extending across said inclined edges and the central portions of the peripheries thereof, whereby the

knurling rollers may be set to cut knurls of the desired depth at a single operation.

3. A knurling tool comprising a shank portion provided with an opening, a carrier-head having a hub portion fitting within the opening in said shank, means for drawing the hub of said carrier-head within the opening in said shank to firmly clamp said carrier-head against the shank and prevent relative movement of said carrier-head and shank, and knurling rollers supported by said carrier-head said rollers being provided with teeth extending across inclined edges and the central portions of the peripheries thereof, whereby the knurling rollers may be set to cut knurls of the desired depth at a single operation.

4. A knurling tool comprising a shank portion, a carrier-head supported by said shank portion, said carrier-head comprising a central hub provided with radial arms, and knurling rollers operatively mounted in said arms, said rollers being provided with inclined edges and having teeth extending across said inclined edges and the central portions of the peripheries thereof.

5. A knurling tool provided with cooperating rollers having inclined edges, and teeth extending diagonally across the inclined edges and the central portion of the peripheries of said rollers, whereby the knurling rollers may be set to cut knurls of the desired depth at a single operation.

In testimony whereof I have affixed my signature.

GEORGE W. DOVER.
